CLAIM

The ornamental design for spectacles, as shown and described.

DESCRIPTION

FIG. 1 is a perspective view from the front left side of the spectacles, where the temples are shown in an extended position;

FIG. 2 is a perspective view from the front of the spectacles of FIG. 1, where the temples are shown in a retracted position;

FIG. 3 is a perspective view from the rear of the spectacles of FIG. 1, where the temples are shown in an extended position;

FIG. 4 is an elevation from the left side of the spectacles of FIG. 1, where the temples are shown in an extended position;

FIG. 5 a top plan view of the spectacles of FIG. 1, where the temples are shown in an extended position;

FIG. 6 is bottom plan view of the spectacles of FIG. 1, where the temples are shown in an extended position; and,

FIG. 7 is a perspective view from the front left side of the spectacles, where the temples are shown in a retracted position.

The broken lines are for illustration only and form no part of the claimed design.
